(74) Attorney, Agent, or Firm — Quickpatents, LLC;
 Kevin Prince(57) **CLAIM**

We claim the ornamental design for a pepper spray holder and laser, as shown and described.

DESCRIPTION

FIG. 1 is a front perspective view of a pepper spray holder and laser, showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing logos in the figures depict environmental matter and form no part of the claimed design.
